US00D663023S

(12) **United States Design Patent** (10) **Patent No.:** **US D663,023 S**
Strong et al. (45) **Date of Patent:** **** Jul. 3, 2012**

(54) **LIQUID DISPENSING SYRINGE**

(75) Inventors: **Warren N. Strong**, Hope, RI (US);
Michael A. Vidal, North Attleborough,
MA (US); **Terrence Woldorf**, Westport,
MA (US)

(73) Assignee: **Nordson Corporation**, Westlake, OH
(US)

(**) Term: **14 Years**

(21) Appl. No.: **29/367,355**

(22) Filed: **Aug. 6, 2010**

Related U.S. Application Data

(62) Division of application No. 29/326,873, filed on Oct. 27, 2008, now Pat. No. Des. 623,291, which is a division of application No. 29/280,974, filed on Jun. 12, 2007, now Pat. No. Des. 588,693.
